UNITED STATES PATENT OFFICE.

TYNG M. LIBBY, OF TACOMA, WASHINGTON, ASSIGNOR TO HENRY G. CORDES, OF BREMERTON, WASHINGTON.

RADIOINTERFERENCE PREVENTER.

1,365,926.

Specification of Letters Patent. Patented Jan. 18, 1921.

Application filed October 21, 1919. Serial No. 332,200.

To all whom it may concern:

Be it known that I, TYNG M. LIBBY, a citizen of the United States, residing at Tacoma, in the county of Pierce and State of Washington, have invented a new and useful Improvement in Radiointerference Preventers.

My invention relates to an improvement in means for counteracting the effect of interfering signals in a receiving oscillatory circuit of a receiving radio signal system when the interfering signals are caused by a transmitting station which emits feebly damped waves, constant amplitude waves or waves in which the rate of change of amplitude is comparatively small as in radio telephony. The preventive means are most effective when the interfering wave is a constant frequency sinusoidal wave differing considerably in length from the wave of the signal selected for reception.

The object of my invention is to provide means whereby interference can be counteracted in an oscillatory circuit without changing the resonant frequency of the circuit.

This object is attained by connecting two reactances in parallel and adjusting one of them for zero value at the resonant frequency of the oscillatory circuit in which the interfering signal current flows. The parallel reactances are then connected in series with the oscillatory circuit and the parallel reactances in series with each other are adjusted for zero value at the frequency of the interfering signal current.

The procedure heretofore has been to connect the parallel reactances in series with the oscillatory circuit, to adjust the parallel reactances in series with each other for zero value at the frequency of the interfering current and then to adjust the reactance of the oscillatory circuit so that the reactance of the oscillatory circuit in series with the parallel reactances will be zero at the frequency of the current of the signal selected for reception or amplification by series resonance.

My improvement will be described more in detail by referring to the drawing forming part of this specification. Figure 1 shows parallel reactances in series with a receiving antenna circuit. Figs. 2, 3 and 4 are modifications of Fig. 1.

Fig. 1 with switch 1 thrown to the right 55 represents diagrammatically a complete

radio signal receiving system of the present radio art. The antenna 2, antenna primary coil 3 and ground connection 4 represent the usual receiving antenna circuit. The coil 5 and condenser 6 constitute the secondary 60 oscillatory circuit of the receiving system. The audion 7, battery 8 and telephone receiver 9 convert the high frequency current into audible sound. The reactances of the antenna circuit and the secondary oscillatory circuit are made zero at the frequency of the waves of the signal selected for reception.

When an interfering signal wave impresses an electromotive force of a different 70 frequency upon the antenna circuit the reactance of inductance 10 and condenser 11 in series is made equal to the reactance of the antenna circuit at resonant frequency and then switch 1 is thrown to the left. The 75 inductance 12 is then adjusted until the reactance of inductance 10, condenser 11 and inductance 12 in series is zero at the frequency of the interfering impressed electromotive force. In Fig. 1 it is assumed that 80 the frequency of the interfering electromotive force is less than the frequency of the impressed electromotive force due to the signal selected for reception. Parallel resonance is attained in the circuit 10-11-12 85 when the interfering current in the antenna circuit is a minimum.

For convenience let the reactance of the antenna circuit be represented by X when switch 1 is thrown to the right. Let the reactance of inductance 10 and condenser 11 in series be represented by Y and let the reactance of inductance 12 be represented by Z. Then both X and Y are zero at the frequency of the waves of the signal selected for 95 reception and Y plus Z equals zero at the frequency of the interfering waves.

The word "frequency" as applied to waves refers throughout this specification to the quantity which is inversely proportional to wavelength or length of the waves.

The total reactance of X in series with Y and Z in parallel will be represented by U which is expressed mathematically by the equation,

$$U = X + \frac{YZ}{Y+Z}$$

from which it is seen that U is zero when both X and Y are zero. For every value of 110

Z there is a second frequency at which **U** equals zero and a third frequency at which **U** equals infinity.

The parallel reactances **Y** and **Z** in series

- 5 when connected in series with **X** will be designated the parallel resonance circuit. The circuit 10—11—12 is the parallel resonance circuit in Fig. 1. The reactance of the series resonance circuit is either **X** when switch is
 10 thrown to the right or **U** when switch 1 is thrown to the left. The parallel resonance circuit constitutes an infinite reactance to current through **X** having the frequency at which parallel resonance takes place.
 15 The method of introducing parallel reactances as described with reference to Fig. 1 is an improvement on the present method which is equivalent to throwing switch 1 to the left, adjusting **Y** plus **Z** for zero reactance at the frequency of the interfering current and then adjusting **X** so that the reactance **U** will be zero at the frequency of the selected signal waves. This method interrupts reception and reactance **X** cannot be
 20 graduated for wavelength since **X** will have different values when **U** equals zero.
 25

By my arrangement and method both the reactance **X** and the reactance of the secondary oscillatory circuit are graduated in the usual manner for wavelength at a given coupling. The reactance **Y** is graduated for wavelengths and before introducing the parallel reactance the reactance **Y** is adjusted to the same wavelength as **X**. The reactance **Z** can also be graduated in arbitrary units so that for every value of reactance **Y** there is a set of values of **Z** which can be tabulated for reference. Reception of the selected signal is not interrupted while **Z** is being adjusted for zero reactance in the parallel resonance circuit at the frequency of the interfering waves.

Fig. 2 illustrates a modification of the parallel resonance circuit of Fig. 1. The condenser 13 is substituted for inductance 12 of Fig. 1 so that the parallel resonance circuit 10—11—13 may be adjusted for zero reactance at a frequency which is greater than the resonant frequency of the antenna circuit when switch 1 is closed. In Fig. 2 the antenna circuit is not broken while the parallel reactances are being introduced into the circuit. In Fig. 1 the reactance **Z** is positive while in Fig. 2 the reactance **Z** is negative. When switch 1 is closed the reactance of the antenna circuit is **X**.

Fig. 3 illustrates another modification of the parallel resonance circuit of Fig. 1. A condenser 13 is placed in series with inductance 12 so that the reactance of the parallel resonance circuit 10—11—13—12 can be made zero at any frequency. The parallel resonance circuit may be adjusted for zero reactance at the frequency of the interfering current either before or after switch 1

is opened depending upon whether the frequency or wavelength of the interfering wave is known as in duplex signaling or is not known.

The resistance of a parallel resonance circuit should be reduced to a minimum since the amplitude of the interfering alternating current flowing in the antenna circuit is proportional to the ohmic resistance in the parallel resonance circuit and the amplitude is also inversely proportional to the product **YZ** when the ohmic resistance is negligible compared to both reactance **Y** and to reactance **Z**. In order to reduce the resistance of reactances **Y** and **Z** in series to a minimum the parallel resonance circuit should consist of a continuous conductor between the dielectrics of the condensers and the condenser dielectric should be air. The conductor should preferably have large surface area per unit length. The inductances can be made in the form of a helix and their value can be varied by varying the length of the helical coil in the direction of its axis. The capacitance of the condensers can be varied in the usual manner by moving one armature or pole of the condenser with respect to the other armature or pole.

Fig. 4 is similar to Fig. 3 except that provision is made to counteract interference from two interfering stations. Interference from the first station is counteracted by the parallel resonance circuit 10—11—13—12 with switch 1 open and switch 18 closed which is equivalent to Fig. 3. When it becomes necessary to counteract interference from a second station the reactance of inductance 14 and condenser 15 in series is made zero at the resonant frequency of the antenna circuit. Switch 18 is then opened and either or both inductances 16 and condenser 17 are adjusted for zero reactance in the second parallel resonance circuit 14—15—17—16 at the frequency of the waves emitted by the second interfering station. Any number of pairs of parallel reactances may thus be connected in series with an oscillatory circuit without changing its resonant frequency.

The present state of the art with respect to preventing interference by means of a parallel resonance circuit is described in the Bureau of Standards Circular No. 74, page 39 *et seq.* In this publication it is noted that by making the capacitance in **Y** equal to the capacitance in **X** and making the inductance in **Y** equal to the inductance in **X** that the reactance **Z** can be varied without changing the frequency at which **U** is zero. This is a special case of my arrangement and is very limited in its application. It may be compared to limiting the capacitance of the secondary oscillatory circuit to the value of the capacitance of the antenna circuit.

My improvement consists in making the product of capacitance and inductance in Y equal to the product of capacitance and inductance in X which allows parallel reactances to be built in a compact form, properly graduated and introduced into any oscillatory circuit without changing the resonant frequency of the circuit provided the products of capacitance and inductance in X and Y can be made equal. Reactances Y and Z can be varied by changing either capacitance or inductance. The current in the parallel resonance circuit is increased as the ratio of inductance to capacitance in Y is decreased.

The reactances X , Y and Z are connected in parallel. The reactance X is distinguished by containing the source of the impressed electromotive force while Y is the reactance which is made equal to X . Either X , Y or Z may be the resultant of a number of reactances in parallel. In order that a reactance can be adjusted to zero it must consist of both inductance and capacitance in series.

The invention claimed is:

1. The combination of two parallel reactances in series with an oscillatory circuit; the first of said reactances being adjusted to zero value at the resonant frequency of said circuit and having inductance differing in value from the inductance of said circuit, and, both of said reactances constituting an infinite reactance in series with said circuit for current in said circuit having a frequency differing from said resonant frequency.

2. The combination of three reactances in parallel, the products of capacitance and inductance of the first and second of said reactances being equal, the capacitances forming part of said first and second reactances being unequal, the third of said reactances having a single path for current and means for impressing electromotive forces of two frequencies in said first reactance.

3. A plurality of pairs of parallel reactances in series with an oscillatory circuit, one of each pair of said reactances being zero at the resonant frequency of said circuit.

4. The method of introducing parallel reactances in series with an oscillatory circuit in which current is flowing without interrupting the flow of current in said circuit and without changing the resonant frequency of said circuit which consists in adjusting one of the parallel reactances for zero value at the resonant frequency of an oscillatory circuit and then introducing said parallel reactances in series with said oscillatory circuit.

5. The method of suppressing an alternating current in an oscillatory circuit which consists in adjusting one of two parallel re-

actances for zero value at the resonant frequency of an oscillatory circuit, introducing said parallel reactances in series with said oscillatory circuit and adjusting the second of said parallel reactances for parallel resonance at the frequency of the alternating current to be suppressed in said oscillatory circuit.

6. The method of suppressing an alternating current in an oscillatory circuit which consists in adjusting a reactance Y of two parallel reactances Y and Z for zero value at the resonant frequency of an oscillatory circuit, adjusting said reactance Z until said reactances Y plus Z become zero at the frequency of the alternating current to be suppressed in said oscillatory circuit and introducing said parallel reactances in series with said oscillatory circuit.

7. A radio frequency alternating current circuit comprising a plurality of parallel resonance circuits, each of said circuits comprising two reactances, one reactance of each parallel resonance circuit being zero at a resonant frequency of said alternating current circuit.

8. An oscillatory circuit comprising a plurality of pairs of parallel reactances, one of each pair of said reactances being zero at a resonant frequency of said circuit and each of said pairs constituting an infinite reactance to current in said circuit having a frequency differing from said resonant frequency.

9. A radio frequency alternating current circuit comprising two parallel reactances, the first of said reactances being adjusted to zero value at a resonant frequency of said circuit and having inductance differing in value from the inductance of said circuit and both of said reactances constituting an infinite reactance for current having a frequency differing from said resonant frequency.

10. An oscillatory circuit in combination with a parallel resonance circuit comprising two reactances, one of said reactances being zero at a resonant frequency of said oscillatory circuit and having inductive reactance differing from the inductive reactance of said oscillatory circuit at said resonant frequency.

11. In combination with a radio frequency current aerial conductor a plurality of parallel resonance circuits, each of said circuits comprising parallel reactances, one parallel reactance of each of said circuits being zero at a resonant frequency of a circuit comprising said conductor.

12. An alternating current circuit having positive and negative components of reactance in combination with means for suppressing current in said circuit; said means comprising zero reactance at a resonant frequency of said circuit and a parallel reso-

5 nance circuit which constitutes a large impedance to current in said alternating current circuit; said zero reactance and said parallel resonance circuit having reactance 5 in common; and, said zero reactance having components differing in value from the components of reactance of said alternating current circuit at said resonant frequency.

- 10 13. Means for suppressing current in a radio aerial circuit comprising a zero reactance at a resonant frequency of said circuit and a parallel resonance circuit which constitutes a large impedance in said radio aerial circuit to current having a frequency 15 at which resonance takes place in said parallel resonance circuit; said zero reactance having components differing in value from the components of reactance of said radio aerial circuit at said resonant frequency.
- 20 14. Means for suppressing current of an undesired frequency in a radio aerial circuit comprising a zero reactance, a parallel resonance circuit which constitutes a large impedance in said aerial circuit to current hav-

ing said undesired frequency and means for 25 keeping said zero reactance constant while reactance comprised by said parallel resonance circuit is varied; said zero reactance having components differing in value from the components of reactance of said radio 30 aerial circuit.

15. A plurality of means for suppressing alternating current in combination with an alternating current circuit, each of said plurality comprising a parallel resonance 35 circuit and a zero reactance at a resonant frequency of said alternating current circuit; each of said zero reactances having components differing in value from the components of reactance of said alternating current circuit at said resonant frequency.

This specification signed and witnessed on this 6th day of October, 1919.
